(57) **CLAIM**

The ornamental design for a flat bottom pouch with partial side gusset and spout, as shown and described.

DESCRIPTION

FIG. 1 is a perspective view of the flat bottom pouch with partial side gusset and spout showing the design;

FIG. 2 is a front view thereof, the rear view is a mirror image thereof;

FIG. 3 is a right side view thereof, the left side view is a mirror image thereof;

FIG. 4 is a top view thereof; and,

FIG. 5 is a bottom view thereof.

1 Claim, 3 Drawing Sheets
